ELECTRICAL SWITCH

Maximilian C. Becker, East Orange, and Leslie N. Crichton, Livingston, N. J., assignors to Westinghouse Electric & Manufacturing Company, East Pittsburgh, Pa., a corporation of Pennsylvania.

Application January 20, 1940, Serial No. 314,836

1 Claim. (Cl. 200—144)

This invention relates to electrical switches, and it has particular relation to electrically operated circuit opening switches.

In many relay applications, it is desirable that a translating device, such as a circuit breaker trip coil, be actuated by an entirely self-contained relay unit. For such an application it is possible to connect the trip coil across a current transformer employed for energizing the relay. Suitable control for the trip coil is provided by a circuit opening switch which is connected normally to by-pass the trip coil. When the relay operates in response to a predetermined condition of an electrical circuit to be protected, such as an overload condition, the circuit opening switch is opened to permit actuation of the trip coil by the current transformer. The relay may be employed for various purposes. For example, it may be a time-delay relay set to permit other relays to operate first, or the relay may be a directional or an impedance relay.

Circuit opening switches of the type herein contemplated must operate under widely varying conditions. Because of the sensitive operation desired and the low energies available for actuation, the circuit opening switch must have a low contact pressure. Despite this low contact pressure, the switch must be capable of passing continuously currents of the order of 3½ to 5 amperes without developing undue resistance. Should undue resistance be developed under these circumstances, an unnecessary and undesirable operation of the trip coil would result.

At the same time, the circuit opening switch must be capable of opening when carrying excessive currents without suffering appreciable damage. When a fault occurs on the circuit being protected, currents of the order of 50 amperes, and occasionally up to 200 amperes, may pass through the contacts of the circuit opening switch. Unless properly designed, a switch will be severely damaged by currents of this magnitude.

Moreover, the frequency of operation of such circuit opening switches depends on the type of service to which the switch is to be subjected. In some applications, the switch may remain closed without a single operation for a period of several years. For other applications, an actuation of the switch may be expected several times an hour. Because of this wide variation in service conditions, the circuit opening switch is subjected to unusually severe duty.

In accordance with our invention, a switch is provided having contacts formed from a noble

metal, such as silver. These contacts are in the form of substantially parallel spaced plates. The only conductive contact between these plates occurs between a small button or protuberance associated with one of the plates and a corresponding small area on the other plate. Because of the large area provided by the plates, an adequate cooling is assured for the contacts under operating conditions. Preferably, the circuit connections for the switch are so disposed that any arc formed between the contacts is urged away from the button or protuberance and away from any supporting elements towards the edges of the contact plates. Consequently, any arcing occurring between the plates can damage only the edges thereof, and does not affect the current-carrying characteristics of the contacts.

According to a further aspect of our invention, a barrier member is provided for partially bridging the contact plates. This barrier member not only may protect the supporting elements for the movable plates, but, in addition, provides with the plates a channel for directing gases formed by an electrical discharge between the plates towards predetermined edges of the plates. Consequently, the gases assist in carrying the electrical discharge towards these edges.

It is, therefore, an object of our invention to provide an electrical circuit opening switch capable of reliable and durable performance.

It is another object of our invention to provide a switch having all current-carrying portions formed of a noble metal.

It is a further object of our invention to provide a circuit opening switch with means for forcing an arc formed between the contacts of the switch away from the normal current-carrying areas of the switch.

It is a further object of our invention to provide a circuit opening switch having contacts provided with relatively small current-carrying portions with connections so disposed that an arc forming between the portions is urged rapidly towards the edges of the contacts.

It is a still further object of our invention to provide a circuit opening switch with a barrier partially bridging the contacts thereof for properly directing gases formed by an electrical discharge taking place between the contacts.

Other objects of our invention will be apparent from the following description taken in conjunction with the accompanying drawing, in which:

Figure 1 is a diagrammatic view, with parts in cross-section of a switch embodying our invention; and

Fig. 2 is an exploded perspective view, partly in cross-section, of switch contacts designed in accordance with our invention.

Referring to the drawing, Fig. 1 shows a circuit opening switch 17 having contacts 15 and 16 which are connected into any desired circuit by means of conductors 14 and 18. Operation of the contacts 15 and 16 is effected by means of an energizing winding 24 which may be connected for energization to any suitable control circuit by means of conductors 25 and 28.

For operating the circuit opening switch 17, a solenoid mechanism is provided which includes a magnetic plunger 29 which is reciprocated by magnetic flux produced by the winding 24. A magnetic circuit is provided for this flux which includes a magnetic frame member 30 having ends terminating adjacent the plunger 29, and having an adjustable magnetic core 31 which may be in threaded engagement with the frame member 30. By adjusting the core 31 relative to the frame member 30 and locking it in place by means of a lock nut 32, the calibration for the circuit opening switch may be adjusted as desired. Preferably, a non-magnetic spacer 33, such as brass or bronze, is affixed to the core 31 in order to prevent direct contact of the core with the plunger 29. In addition, the core 31 may carry a non-magnetic sleeve 34 for guiding the plunger 29. The entire solenoid may be attached to a suitable insulating supporting base 35 by means of suitable screws 36.

The contact 16 is associated for movement with the plunger 29 by providing the contact 15 with a pair of electroconductive supporting strips 37 which are clamped at one end between clamping plates 38 and 39 formed of electroconductive material. These clamping plates may be secured and clamped to the base 35 by means of machine screws 48, which pass through the base 35 and are threaded into a retaining member 41. One of the screws may serve as a terminal for the conductor 18.

The plunger 29 is provided with a cylindrical connecting member 42 having an annular recess 43 for receiving the strips 37. The member 42 may be attached to the plunger in any suitable manner. It will be observed that reciprocation of the plunger 29 carries the movable contact into and out of engagement with the fixed contact 16. Return of the movable contact to the position illustrated in Fig. 1 after an actuation of the circuit closing switch may be effected by gravity, or the strips 37 may be constructed of resilient material to bias the contact 15 against the contact 16.

The contact 16 may be supported from a depending portion of the base 35 by means of a bracket 44 integral with or connected to the contact 16 and attached to the base 35 by means of suitable screws 45.

As shown in the drawing, the contacts 15 and 16 are in the form of substantially parallel spaced plates. The contact 15 may be constructed conveniently of two separate plates 15a and 15b positioned on opposite sides of the strips 37. Attachment of the plates to the strips may be by any suitable means, such as by rivets (not shown).

One of the contact plates, such as the contact 16, preferably is provided with a button or protuberance 16a which normally is in engagement with the contact 15. This protuberance may be formed as an independent electroconductive member affixed to the contact 16, but preferably

is formed by bending the contact 16 upwardly, as illustrated more clearly in Fig. 2. The shape may vary, but preferably the protuberance is substantially hemispherical.

Because of the small contact area between the protuberance 16a and the contact 15 and despite the low total pressure available, a reasonably high unit contact pressure is obtained therebetween. This pressure facilitates the movement of dirt or foreign matter away from the contact area. Moreover, because of the extended area of the contacts 15 and 16, adequate cooling is provided therefor.

The operation of the apparatus thus far described may now be set forth. Under normal conditions, the circuit opening switch 17 remains closed. When the winding 24 is energized suitably the contacts 15 and 16 separate. If the contacts carry substantial current at the time of their separation, a heavy arc may be established therebetween. Because of the destructive effects of such an arc, it is desirable that the arc be removed promptly from the contacts.

As illustrated in Fig. 1, the conductors for the contacts 15 and 16 represented by the conductor 14 and the strips 37 are positioned to provide a magnetic field which assists in urging any arc formed between the contacts 15 and 16 rapidly towards the left of the contacts, as viewed in Fig. 1, until the arc is at the left-hand edges of the contacts. During its movement, the arc travels so rapidly that practically no damage is done to the surfaces of the contacts in the position shown by a dotted line A. Under these conditions, the arc is substantially displaced from the protuberance 16a, which normally establishes contact between the contacts 15 and 16, and no damage can result thereto. The edges of the contacts may, of course, be slightly fused before the arc is extinguished, but since these edges do not normally carry current, the resulting fusion does not affect the performance of the contacts.

It should be noted that the edges which bear the brunt of the arc discharge preferably are always separated. If these edges were in engagement, as in the ordinary type of contact, the fusion produced by an electric discharge would tend to fuse or weld the two contacts together, thereby rendering the circuit opening switch inoperative. Because of the separation which we provide, such fusion or welding cannot take place.

Although the contacts 15 and 16 may be constructed of various materials, we have found that the noble metals, such as gold, silver and platinum, are particularly desirable for the reason that, when subjected to heating from an electric arc, any compounds formed on their surfaces are reduced, leaving only the pure metal. The protuberance 16a could be of a dissimilar material, but preferably all surfaces in the neighborhood of the arc are made of the same material, preferably silver.

When an arc discharge occurs between two metallic surfaces, we have found that a minute metal spray often is produced thereby. If a dissimilar metal or material were provided for the protuberance 16a, the resulting spray would tend to contaminate the material employed for the protuberance. By employing the same material throughout, such contamination is precluded.

It will be noted that the plates 15a and 15b may be substantially similar so that after one plate 15b has seen considerable service, the con-

tact 15 may be reversed to present the contact 15a to the protuberance 16a.

We have found that a further control of any electrical discharge occurring between the contacts may be effected by a flange or barrier 50 partially bridging the contacts 15 and 16. This barrier may be of any suitable material, but conveniently may be formed by bending the material of the plate 15b substantially at right angles. If desired, a similar construction may be employed for the plate 15a to provide complete interchangeability, but normally the plate 15b will not require replacement.

Because of the barrier 50, a channel is provided between the contacts 15, 16 and the barrier 50 which tends to direct gases formed by an electrical discharge between the plates towards the left, as viewed in Fig. 1. Consequently, the gases assist in blowing any electrical discharge between the contacts towards the left-hand edges thereof. In addition, the barrier 50 tends to protect the strips 37 from any flareback of an electrical discharge occurring between the contacts 15 and 16.

Although we have described our invention with reference to certain specific embodiments thereof, numerous modifications thereof are possible.

Therefore, we do not wish our invention to be restricted except as required by the appended claim when interpreted in view of the prior art.

We claim as our invention:

5 In an electrical switch, a pair of substantially parallel contact plates formed of a noble metal, means mounting said plates for movement from a first relationship wherein said plates are spaced from each other for increasing the spacing therebetween, a protuberance formed of said noble metal on a first one of said plates for engaging a predetermined portion of a second one of said plates to establish the only conductive path between said plates when said plates are in said first relationship, the contacting portions of said protuberance and said predetermined portion occupying small, centrally-disposed areas on said plates, and a barrier member formed from a portion of one of said plates and partly bridging said plates for directing gases formed by an electric arc occurring between said plates towards predetermined edges thereof, said protuberance being positioned between said barrier and said edges.
